UNITED STATES PATENT OFFICE.

JOHN H. TODD, OF CLEVELAND, OHIO.

LAUNDRY-CHECKING DEVICE.

1,399,906.

Specification of Letters Patent. Patented Dec. 13, 1921.

Original application filed April 24, 1919, Serial No. 292,326. Divided and this application filed April 15, 1920. Serial No. 374,037.

To all whom it may concern:

Be it known that I, JOHN H. TODD, a citizen of the United States, resident of Cleveland, county of Cuyahoga, and State of Ohio, have invented new and useful Improvements in Laundry-Checking Devices, of which the following is a specification, the principle of the invention being herein explained, and the best mode in which I have 10 contemplated applying that principle so as to distinguish it from other inventions.

The subject matter of this application has been divided out of an application upon laundry checking devices, for which Letters 15 Patent were granted to me under date of June 15, 1920, No. 1,343,423.

My invention relates to checking devices and particularly to devices of this character utilized by laundries. The object of the invention is to design a checking device which 20 will economically and conveniently serve the purpose of making it almost impossible to confuse pieces of laundry belonging to different people.

25 A further object of the invention is to utilize my novel checking device in connection with a receptacle provided with a multiplicity of compartments adapted to hold various pieces of laundry.

30 The annexed drawing and the following description sets forth in detail certain means embodying the invention, the disclosed means, however, constituting but one of the various mechanical forms in which the principle 35 of my invention may be applied.

In said annexed drawing:

Figure 1 represents a perspective view of a cabinet formed with a plurality of separated chambers in which laundry of different classes or belonging to different persons 40 may be segregated, said chambers being severally provided with different keys adapted to coöperate with corresponding check members, the latter being adapted to be secured 45 to the articles belonging in or segregated in the corresponding chambers.

Fig. 2 represents a front elevation of the said key.

Figs. 3 and 4 represent, respectively, side 50 and plan views of the same, the former showing a fragmentary portion of the compartment to which the key is attached, and

Figs. 5 and 6 represent face and side

views, respectively, of the check member employed.

Referring to the annexed drawings, there are represented by the ordinals 1 to 6, respectively, keys of varied shaped cross-sections associated with and attached to the several compartments 8 of a cabinet or receptacle 9. These several compartments are adapted to receive, in a segregated manner, the several pieces of laundry belonging to various classes or various persons. The several keys mentioned comprise a body 65 member 10 formed with longitudinal splines 11 projecting from the faces thereof, the relative disposition of the splines 11 upon the faces of 10, in the form of apparatus herewith shown, being varied, so that only 70 that check member 12 formed with a groove 13 and intersecting apertures 14 corresponding with the key, will fit over any one key. In the form of apparatus herein shown, the check member and corresponding key are 75 indicated by the ordinal "5." The check members 12 are adapted to be secured to the several pieces of laundry by means of pins 15, or any other suitable means.

Heretofore, pins such as those shown in 80 the accompanying drawing by ordinal 15, and provided with different numbers, corresponding to differently numbered compartments of a cabinet such as 9, have been attached to the several pieces of laundry, 85 the same numbered pin being attached to the several pieces of any one compartment. After the garments have been washed and it is desired to segregate into the proper 90 compartment all the pieces bearing the proper number, often the numbers are read wrongly for some reason, such as turning the "6" or "9" upside down, or by putting the wrong piece in the wrong compartment for other reasons. In the checking system 95 45 which I have herein shown and described, all the pieces of laundry of one class are thrown into one of the compartments 8 of the cabinet 9, and as the same are taken out of said compartment, there is attached to 100 each piece one of the check members attached to the key belonging to said compartment. The laundry is then washed with the pins 15 and check members 12 attached thereto and, when it is desired to segregate 105 the pieces of different classes or different

persons, before each piece as described, thereof, and different sets of cards having shown and claimed in said Letters Patent 35
No. 1,343,423, dated June 15, 1920, is put into a compartment 8, Fig. 1, or hung upon
5 a key, the check member 12 attached to the piece is fitted over the proper key 10 and left thereon, Fig. 1, the garment being thrown into that compartment. Inasmuch as the several keys are all different, and in
10asmuch as only one class of check members will fit any one key, and inasmuch as all of the garments of one person or of one class are each provided with a check member having an aperture similar in outline to the outline of the cross-section of that one key only it is impossible to make any errors when segregating the laundry. The length of the splines 11 is immaterial so that the same serve to allow the placing upon the body
15 member 10 of only one class of check-members 12.

My invention is designed not only for use in checking various classes of laundry which should be segregated, but also for checking
20 many articles which temporarily are commingled and later should be segregated into a plurality of definitely defined classes. For instance, it will be readily perceived that this invention may be utilized for library
25 purposes, particularly in checking cards, wherein different positioned splines or splines of different cross-section are formed
30 at the bottom of the card box and interiorly

What I claim is:

1. A checking device comprising a series of open receptacles for the article to be checked, a key fixedly secured to the outer 40 edge of each receptacle adjacent the open end thereof, and a check member adapted to be removably fitted to each key.

2. A laundry checking device comprising a multiplicity of compartments for the reception of articles to be checked, keys fixedly secured to the outer edges of the compartments, each key having a different transverse cross-section, and check members adapted to be removably fitted to the 50 keys, respectively.

3. A laundry checking device comprising a multiplicity of receptacles for receiving the laundry to be checked, a multiplicity of keys fixedly secured adjacent to said receptacles, each key being formed with splines secured in different position thereon, a multiplicity of check members adapted to be secured to the articles to be checked, said check members being formed with apertures 55 corresponding with the cross-sections of said sets of splines, respectively.

Signed by me, this 10th day of April, 1920.

JOHN H. TODD.
